UNITED STATES PATENT OFFICE.

MELVAN L. TWOMLEY, OF ANDERSON, INDIANA, ASSIGNOR, BY MESNE ASSIGNMENTS,
TO SEFTON MANUFACTURING COMPANY, OF MILLBROOK, NEW YORK, A CORPORA-
TION OF NEW YORK.

MANUFACTURE OF PAPER-BOARD.

1,243,013.

Specification of Letters Patent. Patented Oct. 16, 1917.

Application filed March 9, 1912. Serial No. 632,737.

To all whom it may concern:

Be it known that I, MELVAN L. TWOMLEY, a citizen of the United States, residing at Anderson, in the county of Madison and State of Indiana, have invented certain new and useful Improvements in the Manufacture of Paper-Board, of which the following is a specification.

The product referred to comprises a central corrugated strip or sheet of paper upon opposite sides of which are cemented strips or sheets of plain paper the fabric being used for a variety of purposes depending in a measure upon its degree of stiffness, as for carpet lining and packing for which the softer varieties are used and for forming boxes for which the stiffer, harder varieties are used. My invention is not concerned with the application of the first sheet of lining or covering to the corrugated paper but on the contrary it operates upon the intermediate product consisting of the corrugated paper with a sheet of lining applied to one side thereof and completes the product by applying the lining to the other side of the corrugated paper.

Prior to my invention it has been customary in applying the second liner to the fabric to apply the paste to the corrugated sheet and feed the sheets between a pair of rollers so that the liner is pressed into contact with the ridges or ribs of the intermediate, corrugated strip after which the cellular board is fed between the members of a drying device usually consisting of a pair of steam boxes or plates bearing upon opposite sides of the board. A number of objections however are found to the employment of a machine of this character among which may be mentioned that considerable tension must be put upon the board to draw it through the drying device whereby it is sometimes subjected to injury. Another and perhaps more important objection arises from the fact that the paste supplies considerable moisture to the fabric upon its interior which upon reaching the drying device is converted into steam. The board is more or less softened thereby and further the drying is delayed by the confined steam which must escape through the ends of the corrugations or through the body of the fabric before the drying is effectual. It has also been proposed to heat the rollers which ap-

ply the liner to the corrugated fabric and by passing the latter around one of the rollers to secure the necessary drying. This device is of course entirely inapplicable to board which is to be rigid and flat and furthermore the drying is limited by the size of the roller, but a more potent objection to all the devices of the prior art is that by reason of the necessity of drying out the board as described above the operation of the machine is necessarily very slow.

In order to overcome these objections to the machine of the prior art, I provide a machine in which the faces of the fabric which are to be secured together are heated to the highest degree that they will stand without injury just prior to the instant when the cementing material (which is preferably silicate of soda) is applied. The cement is used in the smallest quantity practicable and preferably applied to the ridges or ribs of the corrugated material only. The liner is then applied immediately while the materials to be joined are still exceedingly hot and the latter are next passed directly between a pair of rollers which give the necessary compression to cause them to adhere and the completed fabric is then led away. Ordinarily in the practice of my invention and preferably, I apply no heat whatever after the cement has been applied to the board for I find that the heat which has been transmitted to the adjacent faces of the corrugated and plain papers respectively is amply sufficient to thoroughly and also instantaneously set the cement employed. If desired, however, or found necessary by reason of the character of cement employed or the quantity thereof, further heating of the fabric may be provided for after its component parts are united. An important feature of my invention, however, lies in the fact that by the application of heat to the adjacent faces of the components of the fabric and the immediate application of cement in small quantity and of pressure, the fabric is thoroughly dried, and little or no steam released to injure the same or interfere with the rapidity of operation of the device. By reason of my improvements it is possible to turn out a materially increased quantity of product of improved quality from each machine employed. While I have described below with considerable

detail machines embodying my invention, it is to be understood that my invention is not limited to either or both of them but embraces a wide range of equivalent constructions coming within the scope of the following claims.

In the accompanying drawings forming a part of this application, Figure 1 is a view partly in side elevation and partly in transverse section through a preferred form of machine embodying my invention; Fig. 2 represents a modification of a detail thereof; Fig. 3 is a transverse, vertical section of a slightly modified form of the machine, and Fig. 4 is a rear elevation of a detail. Similar symbols of reference indicate like or corresponding parts throughout the several views.

Turning now to that form of my invention exhibited in Fig. 1, the framework upon which the operating parts are mounted is designated by numeral 6 and consists in a pair of end frames of which but one is shown and between which the rotary parts are journaled. A hollow drum 7 is mounted upon trunnions journaled in the frame one of which is shown at 8 in dotted lines and is hollow to form a passage for a steam pipe 8' by which, in the particular embodiment shown, the drum is heated. Beyond its bearing the trunnion 8 is provided with a pair of belt pulleys 9, the connections of which will be presently explained.

At a suitable point in the framework and as shown above the drum 7, are mounted the pressure rolls 10-11 between which the plain sheet and the corrugated strip lined or faced upon one side are fed together. After the product has passed through the rolls 10-11, it is received between the parallel adjacent faces of a pair of slatted or lagging belts 12-13 by which it is conveyed from the machine and if desired to some point for further treatment. These belts are of a character well known in this art and the upper belt comprises a pair of sprocket chains 14 arranged at opposite sides of the machine and each passing around a forward sprocket 15 and a rear sprocket 16, the two chains being connected by a series of slats 17 connected to alternate links of the chains as shown. The lower belt of lagging is similarly composed, the chains being mounted upon the front and rear sprockets 18 and 19. In Fig. 1 the machine is shown broken away but it will be understood that the horizontal run of the chains is of considerable length. Upon the shaft which bears the lower rear sprocket wheels is keyed a gear 20 which meshes with a gear 21 on the upper rear sprocket shaft to drive the chains in unison, and the gear 20 also meshes with a gear 22 on a stub power shaft 23 which carries a driving pulley 24 driven from any suitable source of power and adapted to be connected

with the gear 22 by any suitable clutch mechanism, indicated in dotted lines at 25. Upon the shaft which carries the upper forward sprockets is keyed a pulley 26 which through the medium of a belt 27 arranged upon one of the pulleys 9 revolves the heating drum 7. Immediately above the drum 7 the paste box 28 is arranged upon parallel horizontal guides 29 and within the box is journaled a paste-applying roller 30 which, by the movement of the box upon its guides, may be brought into operative relation with the lower pressure roll 11 or removed therefrom, and a doctor 31 is adjustable in its bearings toward and from the paste roll to regulate the thickness of the coat of paste thereon. In operation the paste roll is normally driven from one of the pulleys 9 on the heating drum and for this purpose is provided with a belt pulley 32 about which 85 and said pulley 9 the driving belt 33 passes. The pulley 32 is not keyed upon its shaft but is revoluble relative thereto, driving connection between the pulley and shaft being afforded by a ratchet wheel 34 keyed to the shaft and a pawl 35 carried by the pulley 32, the drive obviously being effective only in one direction.

With the construction shown a limited movement of the box 28 on its guides may be 95 had without disturbing the connecting belt 33 by reason of the elasticity and looseness of the latter.

When the machine is stopped it is desirable that the revolution of the paste roller 100 be not suspended for a prolonged period as otherwise a ridge or ridges are apt to be formed thereon at the level of the surface of the paste and I provide mechanism for driving the paste roller when the remainder of the machine is at rest. For this the shaft of the paste roller carries a friction wheel 36 which when the paste roll is withdrawn from its normal operative position may be brought into contact with a friction wheel 110 37 fast upon the shaft 38 of a worm wheel 39. The latter is driven by a worm 40 upon the shaft of an electric motor 41 the current for which is controlled by a switch 42. In this preferred form of construction the 115 shifting of the paste box and roll and energizing of the motor is controlled by the operation of a shifting rod 43. This rod is provided with a pair of pins 51, 51 between which the upper end of the knife switch 42 120 extends, and to its forward end is pivoted a lever 47 fulcrumed upon the frame and carrying at its upper end a segment gear 48. The latter meshes with a gear 49 also journaled in the frame of the machine and bearing upon its shaft an arm 50 connected by a link to the paste box. A suitable handle 44 is provided upon the forward end of the shifting rod or at any other point where considerations of convenience may suggest. 130

It is clear that by moving the shifting rod, the paste receptacle and roll are first withdrawn and then as the movement continues the electric switch is closed, so that the motor 41 is started into operation at about the same time that the friction wheel 37 is engaged by the similar wheel upon the shaft of the paste roller. Below the shifting rod 43 is mounted a second shifting rod 43' having an upwardly turned rear end 45' engaging an arm 45 which operates the clutch 25 for throwing the machine into and out of connection with the power shaft.

The character of this clutch is immaterial, many forms of clutches being known which will answer the purpose. In Fig. 4, however, I have shown a suitable clutch for the purpose in which clutch faces are carried by the pulley 24 and gear 22, the latter being 20 slidably mounted upon shaft 23. A screw 26' is formed or fixed upon the shaft 23 and is engaged by a threaded collar 25' which carries pins 27' engaging a groove 28' upon the hub of pinion 22. It will be understood 25 from this construction that by oscillating the arm 45 the clutch will be thrown into and out of operation.

In practice the operator first throws the machinery into operation by shifting the 30 clutch 25, and the paste roll, which has been theretofore released from operative connection with the electric motor, is thrown into contact with the corrugated paper. When it is desired to stop the machine, a movement 35 of the shifting rod 43' shifts the clutch, and a forward movement of the rod 43 withdraws the paste roll from contact with the corrugated paper brings its friction wheel 36 into contact with the friction wheel 37 40 and starts the motor. By reason of the pawl and ratchet connection 34, 35, the paste roll is revolved without revolving the drum 7 or any of the connecting parts or main machinery when the roll 30 is revolved through 45 the electric motor.

In the construction shown in Fig. 1 an endless belt 52 coöperates with the drum 7 to hold the corrugated paper in close contact therewith and is otherwise guided by 50 the idle rolls 53, 54, 55 and 56. At 57 I have shown a steam box or hollow steam-heated plate supported at one edge close to the bite of the rolls 10-11 by brackets 58 and slanting upwardly therefrom and held 55 in this position by a pair of braces attached to the plate at one end 59 and at the other 60 to an upright 61 forming a part of the framework. Over the upper surface of this steam box passes the liner to be applied 60 to the corrugated paper, and it is held in contact with the steam box by a cast plate 62, pivoted at 63 to the framework, and adjusted by flexible cords or cables 64 passing around and secured to drums 65. The latter 65 are mounted upon journals 66 and may be

adjusted in any well-known manner as by a ratchet and pawl 67 shown in dotted lines in Fig. 1. Between the drum 7 and the compression rolls 10-11 extends a steam-heated breast 68 which in this instance consists in a hollow casting with suitable openings 69 for the supply of steam thereto. The corrugated paper 70 with one lining or facing applied thereto as shown, is fed into the machine and around the drum 7 which is heated by steam admitted through the pipe 8. If a belt or apron 52 is used in connection with this drum the corrugated board or paper is pressed into contact with the latter thereby, or if no apron or belt be employed the corrugated strip or sheet is fed over the roller 54 and around the drum 7 as before but under sufficient tension to hold it closely against the same. From the circumference of the drum 7 the sheet of corrugated material is passed directly into contact with the breast 68 by which it is further heated and brought, so far as the peaks or ridges of the corrugations are concerned, to a high temperature which hardens the corrugation. In 80 this state the board is passed around the lower one of the compression rolls, in the meantime and just before it enters the bite of the rolls being coated with cementing material by roller 30 along a narrow strip at the 85 peak of each corrugation. The silicate of soda or other adhesive employed is applied in the smallest quantity that will satisfactorily accomplish the result aimed at. In the meantime, the sheet of lining, facing material or paper to be applied to the corrugated paper to complete the board is fed down over the steam box 57 and between the latter and the plate 62, so that its lower face, to wit, the side which is to be applied to 90 the corrugated paper is likewise heated to a high temperature and the construction is such that the heating is carried forward practically until the liner enters the bite of the rolls. Thus, at this point, the adjacent 95 faces of the liner and the corrugated paper have been thoroughly dried and heated and the adhesive applied to the latter. The two layers then pass together between the compressing rolls which are so spaced as to exert a slight pressure upon them which causes the layers to adhere together. The product, which now comprises the corrugated paper with a lining on each side thereof, passes in 100 a horizontal plane to and between the endless belts or lagging as shown which permits the fabric to immediately cool. In some instances, with a slow drying cement it may be advisable to employ some suitable heating means as the steam boxes of the 105 prior art. Again if desired, I may substitute for the smooth surfaced drum 7, a drum 7' (see Fig. 2) having corrugations 47 fitting the corrugations of the board. In such a structure the board is more evenly heated 110

though this is not necessary since the cement is only applied to the narrow strips at the apices of the corrugations.

In Fig. 3 of the drawings I have shown 5 a modification embracing certain features of my invention but omitting others. The framework, lagging, pressure rolls and heating means for the lining strip preparatory to its application to the corrugated board, 10 are substantially as in the machine shown in Fig. 1. For the drum 7 of the preferred form, however, I have substituted a stationary heated surface which takes the form of a continuation of the steam heated breast 15 68 shown in Fig. 1 and extends from the front of the machine beneath the paste box and upwardly into proximity to the pressure roll 11. The endless belt 69' serves to hold the cardboard against the breast and 20 is carried by the idle rolls 70', 71 and 72. Power is transmitted to the paste roll from the upper sprocket shaft by belts 73 and 74 which engage pulleys 75 upon the shaft 77 and pulleys on the sprocket shaft and paste 25 roll journal respectively. The paste box 78 is in this instance manipulated by the handle 79 the shaft of which is connected by links 80 and 81 with the paste box.

It will now be seen that in my invention 30 whichever form be adopted the major portion or all of the heating is done before the component parts of the fabric reach the paste applying roller and the compression rolls, and that the heating is applied thereto 35 on the faces which are to be caused to adhere and, though this is so, yet by reason of the propinquity of the adhesive applying roller to the bite of the compression rolls, but little adhesive need be applied and the 40 heat retained by the paper is sufficient ordinarily with a suitable adhesive to cause the evaporation of all the moisture in the adhesive within a very short period after it is applied. It is therefore unnecessary ordinarily to provide further heating means beyond the compression rolls with their attendant disadvantages and slow action as 45 set forth above.

What I claim is:

50 1. In a machine for the manufacture of paper board, a pair of smooth surfaced compression rolls, means for feeding a sheet of corrugated paper lined upon one side thereto, means for feeding a lining sheet 55 thereto, means extending close to the bite of the compression rolls for heating the lining sheet and corrugated sheet respectively directly upon their contiguous surfaces and adhesive applying means arranged between the compression rolls and one of the heating means.

60 2. In a machine for the manufacture of paper board, smooth surfaced means for compressing the board, means for feeding a 65 corrugated strip of paper lined upon one

side and a lining strip thereto, means for applying adhesive to one of said strips just prior to its entry into the bite of the rolls and means for heating both strips directly upon the faces thereof which are to be 70 brought in contact with each other prior to the application of the paste.

3. In a device of the class described, a pair of smooth surfaced compression rolls, a heating drum over which a corrugated strip of 75 paper lined upon one side may be passed, with its corrugations directly in contact therewith arranged in advance of said compression rolls, an adhesive applying roll adjacent one of the compression rolls and adapted to apply adhesive to the strip of paper passing around said roll, means for heating a lining strip arranged adjacent the bite of the rolls and means for receiving and carrying away the completed fabric. 80

4. In a machine of the class described, a pair of compression rolls 10—11, a heating plate 57 arranged adjacent the bite of the rolls and adapted to heat a lining sheet fed to the rolls, a heated drum 7 and a breast 90 adapted to heat a sheet of corrugated paper and to guide it to the compression rolls, a tank 28 and roller 30 for applying paste to the corrugated sheet of paper and endless belts for conveying away the completed 95 fabric.

5. In a machine of the class described, means for bringing the sheets of material into close contact with each other, means for feeding the material through the machine, 100 a paste roll movable into and out of contact with one of the sheets of material being treated, means for driving the paste roll when in contact with the paper, and supplemental means for driving the paste roll 105 when withdrawn from such contact.

6. In a machine of the class described, means for bringing the sheets of material into close contact, means for feeding the material through the machine, a paste roll movable into and out of contact with the material, connections for rotating the roll from the feeding means, and means for rotating the roll when the feeding means is at rest. 110

7. In a machine of the class described, 115 means for bringing the sheets of material into close contact, driven means for receiving the material from the first named means, a paste roll for applying cementing material to one of the sheets before it is brought into 120 contact with the other, connections whereby the paste roll may be driven from said receiving means, and means for driving the paste roll when the receiving means is at rest.

8. In a machine of the class described, 125 means for bringing the sheets of material into close contact, lagging for receiving the material and conveying it from said means, a paste roll movable into and out of contact 130

with the material, connections for rotating the paste roll from the lagging, and means for operating the roll when the lagging is at rest.

- 5 9. In a machine of the class described, means for bringing the sheets of material to be united into contact with each other, lagging for receiving the finished material, driving means for the lagging, a clutch between the lagging and driving means, means for shifting the clutch, a paste roll movable into and out of contact with one of the sheets of material to be united, and means for shifting the roll, means for driving the paste roll when in operative position, and means for driving it when in inoperative position.
10. In a machine of the class described, a pair of pressure rolls, endless belts of lagging adapted and arranged to receive the product from the pressure rolls, a power shaft for driving the lagging, a clutch between said shaft and lagging, means for heating the sheets to be united prior to their entry between the pressure rolls, paste applying means movable toward and from the pressure rolls, and means for moving the paste applying means and means for shifting the clutch.
11. In a machine of the class described,

pressure rolls, lagging for receiving the product therefrom, a power shaft for driving the lagging, a clutch between the power shaft and the lagging, paste applying mechanism movable toward and from the pressure rolls, an electric motor and connections for driving the paste roll when out of operative position, a switch, and a shifting rod for controlling the switch, and the position of the paste applying mechanism.

12. In a machine of the class described, pressure rolls, lagging for receiving the product therefrom, means for driving the lagging, a paste roll movable toward and from one of the sheets of material treated, permanent connections between the roll and the lagging for driving the roll but permitting the latter to be driven by other means when the lagging is idle, said connections also permitting the movement of the paste roll toward and from one of the sheets without interrupting the connection to the lagging, and supplemental driving means into engagement with which the paste roll may be shifted.

Copies of this patent may be obtained for five cents each, by addressing the "Commissioner of Patents, Washington, D. C."

It is hereby certified that the assignee in Letters Patent No. 1,243,013, granted October 16, 1917, upon the application of Melvan L. Twomley, of Anderson, Indiana, for an improvement in "The Manufacture of Paper-Board," was erroneously described and specified as "Sefton Manufacturing Company," whereas said assignee should have been described and specified as *Sefton Manufacturing Corporation*, as shown by the records of assignments in this office; and that the said Letters Patent should be read with this correction therein that the same may conform to the record of the case in the Patent Office.

Signed and sealed this 20th day of November, A. D., 1917.

[SEAL.]

R. F. WHITEHEAD,

Acting Commissioner of Patents.
